(57) **CLAIM**

The ornamental design for an accelerator pedal for vehicles as shown and described.

DESCRIPTION

FIG. 1 is a front view of an accelerator pedal for vehicles of our present design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front right perspective view thereof.

The broken lines depicting a boundary around the de-emphasized elements, and the de-emphasized elements within, illustrate portions of the accelerator pedal for vehicles which form no part of the claimed design.
